US00D794796S

(12) **United States Design Patent** (10) **Patent No.:** **US D794,796 S**
(45) **Date of Patent:** **** Aug. 15, 2017**

(54) **INTERVERTEBRAL IMPLANT**(71) Applicant: **NuVasive, Inc.**, San Diego, CA (US)(72) Inventor: **Erika Lin**, San Diego, CA (US)(73) Assignee: **NuVasive, Inc.**, San Diego, CA (US)(**) Term: **15 Years**(21) Appl. No.: **29/577,261**(22) Filed: **Sep. 12, 2016**

4,878,915 A 11/1989 Brantigan
4,892,545 A 1/1990 Day
4,904,261 A 2/1990 Dove
4,932,975 A 6/1990 Main
4,961,740 A 10/1990 Ray
5,002,576 A 3/1991 Schmitz et al.
5,015,247 A 5/1991 Michelson
5,026,373 A 6/1991 Ray
5,047,055 A 9/1991 Bao
5,055,104 A 10/1991 Ray
5,062,850 A 11/1991 MacMillan
5,071,437 A 12/1991 Steffee
5,171,278 A 12/1992 Pisharodi
5,263,953 A 11/1993 Bagby
5,290,494 A 3/1994 Coombes
5,306,307 A 4/1994 Senter
5,306,309 A 4/1994 Wagner
5,364,400 A 11/1994 Rego
5,397,364 A 3/1995 Kozak
5,405,391 A 4/1995 Hednerson
5,413,602 A 5/1995 Metz-Stavenhagen
5,425,772 A 6/1995 Brantigan
5,431,658 A 7/1995 Moskovich
5,443,514 A 8/1995 Steffee
5,443,515 A 8/1995 Cohen
5,454,811 A 10/1995 Huebner
5,458,638 A 10/1995 Kuslich
5,484,437 A 1/1996 Michelson
5,489,307 A 2/1996 Kuslich
5,489,308 A 2/1996 Kuslich
5,514,180 A 5/1996 Heggeness
5,522,899 A 6/1996 Michelson
5,534,030 A 7/1996 Navarro
5,534,031 A 7/1996 Matsuzaki
5,540,688 A 7/1996 Navas
5,549,612 A 8/1996 Yapp
5,562,736 A 10/1996 Ray
5,571,190 A 11/1996 Ulrich
5,571,192 A 11/1996 Schonhoffer
5,593,409 A 1/1997 Michelson
5,609,636 A 3/1997 Kohrs
5,611,800 A 3/1997 Davis
5,616,144 A 4/1997 Yapp
5,632,747 A 5/1997 Scarborough
5,645,598 A 7/1997 Brosnahan
5,653,761 A 8/1997 Pisharodi
5,653,762 A 8/1997 Pisharodi
5,665,122 A 9/1997 Kambin
5,669,909 A 9/1997 Zdebllick
5,676,703 A 10/1997 Gelbard
5,683,394 A 11/1997 Rinner
5,683,464 A 11/1997 Wagner
5,700,264 A 12/1997 Zucherman

Related U.S. Application Data

(63) Continuation of application No. 29/547,760, filed on Dec. 7, 2015, now Pat. No. Des. 767,137, which is a continuation of application No. 29/469,512, filed on Oct. 10, 2013, now Pat. No. Des. 745,159.
